The ornamental design for a flexible electronic device, as shown and described.

DESCRIPTION

FIG. 1 is a perspective view of a flexible electronic device showing the new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of the new design shown in a first bending position;

FIG. 9 is a left side view of FIG. 8;

FIG. 10 is a perspective view of the new design shown in a second bending position;

FIG. 11 is a left side view of FIG. 10;

FIG. 12 is a perspective view of the new design shown in a third bending position;

FIG. 13 is a left side view of FIG. 12; and,

FIG. 14 is another perspective view of the new design shown in the third bending position.
